UNITED STATES PATENT OFFICE.

WALTER H. COLES, OF TROY, OHIO.

IRRIGATING APPARATUS.

Application filed October 26, 1921, Serial No. 510,635. Renewed October 6, 1925.

This invention relates generally to irrigating apparatus and has for its main object and feature the production of simple means for oscillating a sprinkler pipe and supplying water thereto.

In the accompanying drawings, the invention is disclosed in one concrete and preferred embodiment in which.

Fig. 1 is a view in front elevation, partly broken away, of an irrigating apparatus embodying the invention.

Fig. 2 is a vertical sectional view on the plane of line 2—2 of Fig. 1.

Fig. 3 is a vertical sectional view on the plane of line 3—3 of Fig. 2.

Fig. 4 is a vertical sectional view on the plane of line 4—4 of Fig. 2.

Fig. 5 is a vertical sectional view on the plane of line 5—5 of Fig. 2.

1 indicates a casing, here circular in form, and 2 is a paddle movable in opposite directions within said casing. Suitable valve mechanism is provided for admitting and exhausting water to and from the casing alternately on opposite sides of the paddle, and the oscillating motion of the paddle thus produced is used to oscillate a sprinkler pipe.

This motion may be imparted to the sprinkler pipe in any suitable way, as by means of gears, but preferably, and as herein disclosed, the paddle is mounted fast on oscillatory sprinkler pipe 3 which latter extends through the casing. The valve mechanisms are, in the present instance, constructed as follows: 4

5 indicates a partition wall in casing 1 and in this partition are located two valves 5 and 6. Valve 5 is an admission valve and is located in an opening 7 having communication with conduit 8 leading from the water supply; and

40 valve 6 is an exhaust valve and is located in an opening 9 having preferably, but not necessarily, communication with a conduit 10 in communication with sprinkler pipe 3. 11 and 12 indicate two rockshafts, one on each

45 side of partition wall 4, and each of these rockshafts is provided with two dogs 13 and 14 engaging respectively valves 5 and 6. When the dogs on rockshaft 11 actuate the valves as shown in Figs. 3 and 4, communication

50 will be established between conduit 8 and the casing on one side of partition 4 and between conduit 10 and the casing on the other side of partition 4; and when the dogs on rockshaft 12 act, conduits 8 and 10 will

55 come into communication with the casing in

reverse relation to that previously established. Said valve mechanism may be operated by hand, but preferably, and as herein shown, it is operated automatically, and, in the particular form here disclosed, it is actuated indirectly from the paddle through the instrumentality of the sprinkler pipe.

As here shown, 15 indicates an oscillatory weight mounted loosely on the sprinkler pipe. Mounted fast on said pipe are arms 16 and 17 and, as said pipe moves

60 to the left in Fig. 1, arm 17 will raise weight 15 until it passes over the dead center when the weight will drop and strike

65 arm 18 on rockshaft 12 thereby actuating the valves and reversing the movement 70 of the paddle. Arm 16 will now raise the weight and the latter will then drop on arm 19 of rockshaft 11 thereof, again reversing

75 the valves and so on.

20 indicates a source of supply of water having a valve 21 which, when open, admits water to conduit 8 and another valve 22 which, when open, admits water to conduit

80 10. In the present case, both the exhaust water from valve 6 and the water from valve 22 flows to chamber 23 secured to the

85 casing and into which the sprinkler pipe extends and with which it communicates. By adjusting valves 21 and 22, the speed of paddle 2 may be regulated while maintaining

90 constant the flow of water to sprinkler pipe 3.

I claim:

1. Irrigating apparatus including: a casing, an oscillatory sprinkler pipe extending through said casing, a paddle within said casing and mounted fast on said pipe, reversible valve mechanism for supplying and exhausting water to and from said casing alternately on opposite sides of the paddle, means for 95 conducting exhaust water from said valve mechanism to said pipe, and means for supplying water to said valve mechanism and to said pipe independently of the valve mechanism.

2. Irrigating apparatus including: a casing, an oscillatory sprinkler pipe extending through said casing, a paddle within said casing and mounted fast on said pipe, reversible valve mechanism for supplying and exhausting water to and from said casing alternately on opposite sides of the paddle, means for conducting exhaust water from said valve mechanism to said pipe, means for 105 supplying water to said valve mechanism and

100

105

110

to said pipe independently of the valve mechanism, and means for reversing the valve mechanism by the movement of the paddle.

3. Irrigating apparatus including: a casing, an oscillatory sprinkler pipe extending through said casing, a paddle within said casing mounted fast on the pipe, reversible valve mechanism for supplying and exhausting water to and from said casing alternately on opposite sides of the paddle, a weight, for reversing the valve mechanism, mounted loosely on the pipe, and means fast on the pipe for raising said weight into a position where gravity becomes effective.

15 4. Irrigating apparatus including: a casing, an oscillatory sprinkler pipe extending through said casing, a chamber adjacent said casing and communicating with said pipe, a paddle mounted fast on said pipe, a source of 20 supply of water, a reversible valve mechanism for admitting and exhausting water to and from the casing on opposite sides of the paddle, the exhaust water passing to the chamber aforesaid, and a conduit for supplying water to the chamber independently of the valve mechanism.

30 5. An irrigating system including: an oscillatory sprinkler pipe, a casing, a paddle movable in opposite directions within the casing, a source of supply of water, connections and reversible valve mechanism within the casing and mounted independently of the paddle to supply and exhaust water to and from said casing alternately on opposite sides of said paddle and to supply uninterrupted 35 flow of water to the sprinkler pipe, and means to oscillate the sprinkler pipe from the paddle once to each oscillation of said paddle.

40 6. An irrigating system including: an oscillatory sprinkler pipe, a casing, a paddle movable in opposite directions within the casing, a source of supply of water, connections and reversible valve mechanism within the casing and mounted independently of the

paddle to supply and exhaust water to and 45 from said casing alternately on opposite sides of said paddle and to supply uninterrupted flow of water to the sprinkler pipe, means to oscillate the sprinkler pipe from the paddle and a connection to lead the exhaust water from the casing to the sprinkler pipe.

50 7. An irrigating system including: a casing, a paddle movable in opposite directions within the casing, an oscillatory sprinkler pipe actuated by said paddle and making one 55 oscillation to each oscillation of said paddle, two valve mechanisms movable in the same direction to simultaneously supply water to and exhaust water from the casing on opposite 60 sides of the paddle, means controlled by the movement of the paddle to actuate both of said valve mechanisms alternately in opposite directions, and means to uninterruptedly supply water to one of said valve mechanisms and to the sprinkler pipe independently 65 of each other.

70 8. An irrigating system including: a casing, a paddle movable in opposite directions within the casing, an oscillatory sprinkler pipe actuated by said paddle and making one oscillation to each oscillation of said paddle, a partition wall dividing said casing, two valve mechanisms movable in the same direction located in said partition wall to simultaneously supply water to and exhaust water 75 from the casing on opposite sides of the partition wall, means controlled by the movement of the paddle to actuate both of said valve mechanisms alternately in opposite directions, and means to uninterruptedly supply 80 water to one of said valve mechanisms and to the sprinkler pipe independently of each other.

85 Signed at Troy, in the county of Miami, and State of Ohio, this 19 day of October, 1921.

WALTER H. COLES.
